PLANT STAKE

Charles H. Stake, 346 Vine St., Sunbury, Pa. 17801

Filed May 1, 1975, Ser. No. 573,467

Term of patent 14 years

Int. Cl. D11—02

U.S. Cl. D35—1

FIG. 1.

FIG. 2.

FIG. 3.

FIG. 4.

FIG. 5.

FIG. 6.

FIG. 1 is a perspective view of the subject design as viewed from the front looking toward one end thereof;

FIG. 2 is a similar front perspective view thereof looking toward the opposite end;

FIG. 3 is a rear elevational view thereof;

FIG. 4 is a side elevational view thereof;

FIG. 5 is an enlarged transverse sectional view taken along line 5-5 of FIG. 3; and

FIG. 6 is an enlarged transverse sectional view taken along line 6-6 of FIG. 3.

I claim:

The ornamental design for a plant stake, substantially as shown.
